UNITED STATES PATENT OFFICE

115,288

DESIGN FOR A MECHANICAL PENCIL OR SIMILAR ARTICLE

Ned D. Fish, Fort Madison, Iowa, assignor to W.
A. Sheaffer Pen Company, Fort Madison, Iowa,
a corporation of Delaware

Application November 12, 1938, Serial No. 81,046

Term of patent 14 years

To all whom it may concern:

Be it known, that I, Ned D. Fish, a citizen of the United States, residing at Fort Madison, in the county of Lee and State of Iowa, have invented a new, original, and ornamental Design for a Mechanical Pencil or Similar Article, of which the following is a specification, reference being had to the accompanying drawing, forming a part thereof.

The figure is a front elevational view of a mechanical pencil or similar article showing my new design.

The dominant feature of my design resides in the provision of an ornamental surface embellishment consisting of laterally extending peripheral grooves over substantially the entire length of the pencil interrupted over a medial portion by a smooth surface.

I claim:

The ornamental design for a mechanical pencil or similar article, substantially as shown and described.

NED D. FISH.
